(57) **CLAIM**

The ornamental design for a head mounted display with phone receptacle, as shown and described.

DESCRIPTION

FIG. 1 is a front isometric view of a head mounted display with phone receptacle showing my new design in a first configuration.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a front isometric view thereof shown in an alternate configuration.

Any broken lines in the Figures are for illustrative purposes only and form no part of the claimed design.

1 Claim, 8 Drawing Sheets
